UNITED STATES PATENT OFFICE.

FREDERICK DOWLING AND ERNEST C. BANNISTER, OF GLEN COVE, NEW YORK.

REMOVABLE SASH-CORD FASTENER.

Application filed March 16, 1923. Serial No. 625,631.

To all whom it may concern:

Be it known that we, FREDERICK DOWLING and ERNEST C. BANNISTER, each a citizen of the United States, residing at Glen Cove, in 5 the county of Nassau and State of New York, have invented certain new and useful Improvements in Removable Sash-Cord Fasteners, of which the following is a specification.

10 This invention relates to a means for attaching the cords which connect the sashes of windows and their balancing weights, to the said sashes, the invention having for an object to provide an improved fastening 15 means which permits of the cord being replaced in the event of breakage without removing the sash from the window frame.

For further comprehension of the invention, and of the objects and advantages 20 thereof, reference will be had to the following description and accompanying drawings, and to the appended claims in which the various novel features of the invention are more particularly set forth.

25 Fig. 1 of the drawings is an edge view of the upper portion of a window sash, showing my improved cord securing device in position thereon.

Fig. 2 is a vertical section on the line 2—2 30 of Fig. 1.

Fig. 3 is a detail perspective view of the main bracket of the device.

Fig. 4 is a horizontal section on the line 4—4 of Fig. 1.

35 In the drawing we have indicated at 10 a portion of a window sash of ordinary construction. In the opposite edges of this sash at the top thereof, are formed the channeled recesses such as 11 in which the cord 40 securing devices are located. Since both of these devices are the same only one need be described. This device comprises a trough-like bracket 12 made of sheet metal and which fits snugly in the recess 11, extending 45 vertically up the side of the sash, this member comprising the main body 12' and the side wings 12a. At the top the main body 12' is extended beyond the side elements 12a and is bent horizontally to lie upon the top of 50 the sash as at 14, this top portion being formed with a number of holes 15 to receive fastening screws 16 which pass therethrough into the sash. The body member 12' is also slotted upwardly from the bottom as at 17 to 55 engage over the shank of a screw 18 threaded into the side of the sash, the head 18' of

the screw overlying the sides of the slot and so retaining the lower end of the bracket from outward displacement.

Struck out from the side wings 12' are a 60 series of tongues 20 which are arranged in staggered relation on the opposite walls and which are of sufficient length to bite into the sash cord 21 inserted therebetween and the opposite wall, when at an angle approaching the horizontal. The outer ends of these tongues are preferably cut obliquely as shown.

When inserting the sash cord 21 in the bracket the tongues 20 are bent to an inclination somewhat greater than that shown in Fig. 1, permitting the cords to be inserted 70 easily in the bracket, being forced upward to the position shown as the bracket is positioned in the recess 11. To this end we pro-

75 vide a flat strip 25 which is placed in contact with the rear face of the body element 12' and which is formed with a number of ratchet like projections or teeth 26 which project through vertical slots 27 in the ele- 80

ment 12' under the respective tongues 20. This flat strip has a laterally bent top portion 29 which lies under the element 14 and the teeth 26 are so arranged thereon with respect to the tongues 20 as to engage the under faces of the latter when the same are bent to the inclined position just referred to, with the two parts 14 and 29 spaced a slight distance apart, the part 29 having openings 85 therein corresponding to the openings 15, 90 while the strip 25 has a slot in its lower end corresponding to the slot 17.

When a new cord is to be connected to the sash 10, the screws 16 are loosened and the attaching device pulled upwardly to remove it from the recess 11. The old cord is removed and the tongues 20 are bent downward, the new cord being then inserted in the bracket 12. The bracket 12 and strip 25 are then inserted together into the recess until the element 29 on the strap engages the top of the sash. The screws 16 are then inserted into place and it will be apparent that as the screws are tightened up the bracket 12 and strap 25 will have a relative longitudinal movement which causes the teeth 26 to force the tongues 20 upward to bite into the sides of the cord. As will be understood, the screw 18 in the lower end of the recess prevents lateral movement of the lower end of the bracket.

While we have illustrated and described

a preferred embodiment of our invention it is to be understood that we do not limit ourselves to the precise construction herein disclosed and the right is reserved to all changes and modifications coming within the spirit and scope of the invention as defined in the appended claims.

Having thus described our invention what we claim as new and desire to protect by Letters Patent of the United States is as follows:

1. A device of the class described comprising a channeled bracket adapted to be inserted downwardly into a recess in the side 15 of a window sash, means accessible from the top of the sash for securing the bracket to the latter, tongues projected inwardly from the sides of the bracket and adapted to grip a sash cord, and means operable from the 20 top of the sash for swinging said tongues into gripping relation with the cord.

2. A device of the class described comprising a channeled bracket adapted to be inserted downwardly into a recess in the side 25 of a window sash, means accessible from the top of the sash for securing the bracket to the latter, tongues projected inwardly from the sides of the bracket and adapted to grip a sash cord, and means operable from the 30 top of the sash for swinging said tongues into gripping relation with the cord, said last means comprising a strip extending along the bracket and having projections passing through slots in the latter and engaging under the tongues thereon.

3. A device of the class described comprising a channeled bracket adapted to be

inserted downwardly into a recess in the side of a window sash, means accessible from the top of the sash for securing the bracket to the latter, tongues projected inwardly from the sides of the bracket and adapted to grip a sash cord, and means operable from the top of the sash for swinging said tongues into gripping relation with the cord, said last means comprising a strip extending along the bracket and having projections passing through slots in the latter and engaging under the tongues thereon, said bracket and strip having laterally offset ends 40 adapted to be drawn together, and thereby move the tongues into gripping relation to the sash cord, by fastening screws passed therethrough to secure the device to the window sash.

4. A device of the class described comprising a bracket adapted to be inserted downwardly into a recess in the side of a window sash, means accessible from the top of the sash for securing the bracket to the latter, said means including a horizontal offset on the upper end of the bracket adapted to project over the top of the sash, sash cord gripping members on said bracket, and fixed elements on the window sash adapted to engage said gripping members and automatically move them toward the sash cord during the final downward movement of said bracket which brings said offset into engagement with the top of the sash.

In testimony whereof we have affixed our signatures.

FREDERICK DOWLING.
ERNEST C. BANNISTER.
